BASE FOR AN ADJUSTABLE LAMP OR SIMILAR ARTICLE

Eivind Kirkeby, Malerhaugveien 15, Oslo, Norway

Filed Nov. 29, 1962, Ser. No. 72,652

Term of patent 7 years

(Cl. D48—20)

FIGURE 1 is a perspective view of a base for an adjustable lamp or similar article showing my new design, with an adjustable lamp shown in dotted lines for illustrative purposes only;

FIGURES 4 and 5 are front and rear elevations respectively; and

I claim:

The ornamental design for a base for an adjustable lamp or similar article, as shown and described.
